UNITED STATES PATENT OFFICE.

CHARLEY A. PHILLIPS, OF ROCKY RIVER, OHIO, ASSIGNOR OF ONE-HALF TO
CHESTER H. PERKINS, OF ROCKY RIVER, OHIO.

WINDOW-SCREEN.

SPECIFICATION forming part of Letters Patent No. 716,751, dated December 23, 1902.

Application filed June 4, 1902. Serial No. 110,221. (No model.)

To all whom it may concern:

Be it known that I, CHARLEY A. PHILLIPS, a citizen of the United States, residing at Rocky River, in the county of Cuyahoga and State 5 of Ohio, have invented certain new and useful Improvements in Window-Screens; and I do declare that the following is a full, clear, and exact description of the invention, which will enable others skilled in the art to which 10 it appertains to make and use the same.

My invention relates to window-screens; and the object of the invention is to provide a screen which is adapted to roll up and unroll as the window is closed or opened, all 15 substantially as shown and described, and particularly pointed out in the claims.

In the accompanying drawings, Figure 1 is a perspective elevation of a window equipped with my improved screen and showing the 20 lower sash partly raised and the screen drawn out proportionately. Fig. 2 is a perspective elevation of a portion of window-casing and showing also a section of the lower sash and a section of window-screening connected 25 therewith and wound about the roller, as hereinafter fully described. Fig. 3 is a perspective elevation of a jointed weather-strip adapted to be attached to the lower sash, as seen in part in Fig. 2. Fig. 4 is a perspective 30 view of the strip which secures the screen to the sash relatively, also, as seen in Fig. 2. Fig. 5 is a cross-section of the sash and the window-casing and sash-guide confining plates at the edge of the sash for the screen, 35 as hereinafter fully described. Fig. 6 is a cross-section of the window-casing, the lower sash, and the screen and its support and other parts connected therewith, also as hereinafter fully described. Fig. 7 is a perspective 40 view of the sectional covering-plate for the screen-roll, and Fig. 8 is a cross-section of the part shown in Fig. 4 on line x-x thereof.

As thus shown and described, it will be seen that the invention comprises a new and 45 original adaptation of a screen to a window. In this adaptation the principle of a rolled screen is employed, and it is intended alike for the upper and the lower sashes of a window, and it is fashioned, as here shown, to be 50 arranged upon the outside of a window. In the main the construction for both sashes is

the same and the principle of operation is identical; but in this instance the views illustrate more particularly the construction and arrangement of parts associated with the 55 lower sash. As such, A represents the said lower sash, and B the window-casing. C represents the screen, and D the roll therefor. This roll is designed to automatically take up the screen and to hold it taut under spring 60 tension, and any suitable spring arrangement connected with the roll D for this purpose may be employed, and such spring need simply have enough power to keep the screen stretched when in use and to automatically 65 roll the same when the sash is lowered. The said roll is secured in suitable bearings d at its ends in the sides of the window-casing, and the roll itself and screen are protected from outside weather or moisture by the shield- 70 plate E. This plate is preferably made in two sections or parts which overlap at their meeting ends and are thus adapted to be used for windows of greater or less width, and the said plate is secured to the window-sill along its 75 lower edge. This leaves an exposed edge along the top of the plate next to the sash when the sash is down, and this exposed portion or opening is effectually covered and kept dry when the sash is down by the right-angled weather- 80 strip F, Fig. 3. This strip likewise is in two sections or parts like the plate E and is similarly adaptable to windows of different width, and its rear flange is secured to the sash-rod, while its lower flange projects out from the 85 plate E and forms a perfect shield at this point.

Screen C is secured to the sash A by means of the strip G. (Shown in Fig. 4.) This strip is also preferably made out of suitable 90 thin sheet metal, such as tin or the like, and in this instance is shown as having three laps 1, 2, and 3, respectively, and it is secured to the sash A through its inner lap or portion, which projects out from the other portion, as 95 shown, and may have one or more holes through which to fasten it, while its outer lap 3 is spaced apart slightly from lap 2 and has an inturned lower edge. By this means I can secure the end of the screen in said 100 part G by inserting the end edgewise therein and pocketing the selvage upon the edge of

the screen within the portions 3 of this holder, and the lower edge 4 thereof is sufficient to engage the selvage and hold the screen in place without other means of fastening.

5 Upon this part G there are also shown downward projections *g* at its ends, which serve as stops or limits to the winding up of the screen when it comes to its end thereof.

The side edges of the screen when open are 10 protected by the double-sided guards H, which are secured to the casing D and are spaced apart just far enough for the screen to have a free runway therein. Usually and preferably I make this guard by bending a piece of 15 sheet metal back upon itself and then bending it at right angles to fasten it to the casing from one angle, while the other sides thereof serve as the guards of the screen, as described and as plainly shown in Figs. 2 20 and 5. In this way the screen is caused to hold its proper relation at the edges, and the said edges are also perfectly closed against entrance from the outside.

Referring to Fig. 2, it will be seen that the 25 outer guard and shield-plate h for the screen has a slit 6 vertically therein, running some distance above the roller, which affords a yielding portion at this point, adapting it to the free movement of the screen and its connections, especially when the window is 30 opened. It will be noticed also that the plate G, which supports the screen upon the window-sash, has its overlapped portions shortened sufficiently at their ends to clear the 35 guard and guide-plates H, and thus allow said guide-plates to extend as far out practically as the sash will go and not be interfered with when the sash is closed. The same general principle will be obtained with the other 40 sash.

Several material advantages follow from the foregoing construction. In the first place by removing the screw 8, by which the screen is fastened temporarily to the sash A through 45 hole 9, I can leave the screen in its casing and have the window free for washing or for raising and lowering without the screen, and then since the shield E is closed, so as to protect the screen within from the weather and rain, 50 it is safe from water when the window is washed, and it is always kept dry and may remain in position through the winter without sustaining any injury. Then, again, this cover E and the side strips along the edge of 55 the window-shield have the additional advantage of serving as weather-strips, so that they really perform a double function, and besides protecting the screen they keep out

the cold air in winter. This is a material feature in a construction of this kind.

One or more screws or like fasteners 8 may be used for each of the screen-plates G, according to convenience.

What I claim is—

1. A window-screen and a roller on which 65 it is wrapped, in combination with a sash and plate thereon engaging the face of the screen near the edge, and having an outer reversely-lapped portion with an inturned edge engaging the edge of the screen, substantially as 70 set forth.

2. In roller-screens for windows, a roller and a screen thereon, in combination with a window-sash and a cross-piece fixed to the edge of the screen and a strip for temporarily securing the same to the sash, comprising a sheet-metal piece lapped back upon itself and providing a channel for engaging the edge of the screen and the outer lap having an in-turned edge to engage the screen in said channel, substantially as shown.

3. The sash of a window having a screen-fastening strip secured to its lower edge and consisting of sheet metal bent back upon itself lengthwise in three laps, and providing an open channel between the two outer laps to engage the screen and having downward projections, *g*, at its ends, in combination with a screen engaged in said strip and a spring-tension roller carrying the screen, and means 90 to secure said roller rotatably in a fixed position, substantially as set forth.

4. In windows, the screen and the roller therefor and the sash to which it is fixed, in combination with the window-casing and a 95 shield for the side edge of the screen consisting of plates having the screen between them and the outer of said plates having a slot 6 vertically in its lower portion to afford a free movement of the screen, substantially as 100 shown.

5. The combination of the roller and the screen thereon, with the window sash and plate G fixed to its lower edge and provided with overlapped portions 1, 2, and 3 and edge 105 4 and having extension *g* at its ends outside said overlapped portions and the shield and guide-plates H for the side edges of the screen having outer portions *h* with slots 6 at their lower ends, substantially as shown.

Witness my hand to the foregoing specification this 20th day of May, 1902.

CHARLEY A. PHILLIPS.
